FITTING FOR FLEXIBLE ELEMENTS

James B. Rishel, Plattsmouth, Nebr.

Application March 22, 1945, Serial No. 584,220

1 Claim. (Cl. 24—115)

(Granted under the act of March 3, 1883, as amended April 30, 1928; 370 O. G. 757)

1

The invention described herein may be manufactured and used by or for Government for governmental purposes, without the payment to me of any royalty thereon.

This invention relates to a fitting which may be secured to the end of a flexible element, such as a rope or cable, and has for an object the provision of an improved fitting of this type.

The ropes that are used for towing gliders require some kind of fitting or eye on the end that is attached to the tow plane to permit attaching the rope to a quick release mechanism on the tow plane. Heretofore it has been the practice to form an eye splice at the end of the tow rope for this purpose. It requires considerable time and special tools to form an eye splice on a nylon rope of the type used for glider tow ropes. Furthermore, this work frequently has to be done in the field where the necessary tools are not available. This places an additional burden upon the maintenance personnel and also ties up important equipment while the eye splice is being formed. The need of a fitting that may be attached to a glider tow rope firmly and securely without difficulty and without special tools has long been realized. A solution to the problem of providing such a fitting is acquired in accordance with this invention.

It is therefore a further object to provide an improved fitting that may be quickly attached to a flexible element firmly and securely without difficulty and without special tools.

A still further object is to provide an improved fitting that may be secured to a flexible element by a simple loop which may be formed by hand.

With the foregoing and other objects in view, which will appear as the description proceeds, the invention resides in the combination and arrangement of parts and in the details of construction hereinafter described and claimed.

Referring to the drawings:

Fig. 1 is a plan view of one form of the fitting provided by this invention, with parts broken away for the sake of clearness, and showing a rope as attached thereto;

Fig. 2 is a side elevation of the fitting illustrated in Fig. 1;

Fig. 3 is a transverse sectional view taken on line 3—3 in Fig. 1;

Fig. 4 is a partial plan view with parts broken away of the fitting of Fig. 1 when employed with a rope that does not contain communication conductors.

Referring to the drawings in detail, Figs. 1 to 3, inclusive, illustrates one embodiment of a fit-

2

ting in accordance with this invention for quickly, securely, and easily attaching to a glider tow rope of the type having intercommunication wire woven therein. The fitting embodies an elongated main body portion indicated by the reference character 10, said body portion having a chamber or recess 11 formed therein, and a cover plate 12 for the recess. The recess 11 is generally elliptical shaped and may be generally defined by side wall portions 13 and 14, end wall portions 15 and 16, and a bottom wall 17. Another recess or channel 18 is formed in the rear wall portion 16 and extends from the rear of the fitting to the recess 11 for leading a flexible element to the recess 11.

A substantially heart shaped lug 19, located within the confines of the recess 11, is formed integrally with the bottom wall 17 and extends upwardly substantially flush with the top of the side and end wall portions. A threaded hole is provided in the bottom wall 17 for receiving a bolt 24. The lug 19 and the bolt 24 are spaced from each other longitudinally of the recess 11 and substantially in line with the channel 18. These elements are utilized in a manner that will be explained hereinafter for securing the fitting to a flexible element, such as, a rope or the like. A hole 20 is also provided in the bottom wall 17 so that an end of a flexible element may be passed therethrough to the outside of the recess 11 to permit fittings such as, communications plugs to be easily attached thereto.

A rope 21 is shown attached to the fitting in the normal manner. This rope is the nylon type that is generally used for towing gliders and it has intercommunication conductors 22 woven into the strands thereof. To secure the fitting to the rope 21, the bolt 24 is first positioned as shown in Fig. 1, then an end of the rope 21 is pushed through the hole 20, then the rope 21 is passed around one side of the bolt 24, then once around the lug 19, and then again around the same side of the bolt 24 as before but in the opposite direction, and then out of the recess 11 through the channel 18. Then the bolt 24 is removed and the cover plate 12 is placed into position and fastened down with bolts 24 and 25 and four screws 26. The next step is to install a communication plug 27 onto the communication conductors 22 and the connection is complete.

An important feature of the invention is that as tension is applied to the rope 21, the outside turn of the rope, indicated by A, is drawn down against the inside turn, indicated by B, this action forces the inside turn B down tightly

against the bolt 24. It will thus be seen that the end of the rope 21 is firmly held in the fitting by snubbing action of the lug 19 and the bolt 24 on the rope 21, and the additional longitudinal snubbing between the turns A and B, from point x to point y, or for that portion where the turns contact each other as they pass around the bolt 24. Most of the holding force is obtained by friction between the turns A and B from point x to point y.

As illustrated by the drawings, when the connection of the fitting to the rope is completed, the rope fits snugly in the recess 11 and the wall portions defining the recess and the cover plate prevents the loops from shifting in a direction transverse to the fitting when tension is applied to the rope.

A quick attaching means, indicated generally by the reference character 30, is provided at the front end of the fitting for quickly attaching the same to some object, such as a tow plane.

Fig. 4 illustrates a slightly varied form of the device of Fig. 1 that may be used with a plain rope 21 that does not carry communication conductors. In this embodiment the hole 20 is omitted as it is not necessary to attach a communications plug, such as illustrated in the above described embodiment. The complete connection comprises simply looping the rope once about the lug 19 and twice about the bolt 24 and fastening the cover plate 12 in position as illustrated. When tension is applied to the rope 21, the outside turn A of the rope is drawn down against the inside turn B and forces the inside turn down tightly against the bolt 24. As in the previous embodiment the end of the rope 21 is firmly held in the fitting by snubbing action of the lug 19 and the bolt 24 on the rope, and the additional longitudinal snubbing between the turns A and B, from point x to point y, or for that portion where the turns contact each other as they pass around the bolt 24. As in the previous embodiment, most of the holding force is obtained by friction between the turns A and B from point x to point y.

From the foregoing description and the drawings it is seen that the rope may be quickly and securely attached to the fitting without difficulty and without special tools, simply by means of a loop which may be formed by hand.

It will be obvious to those skilled in the art that variations may be made in the structure without departing from the spirit of the invention as defined in the appended claim.

I claim:

5 A terminal fitting for a flexible element such as a cable, rope and the like comprising in combination with the flexible element an elongated rigid terminal body member having a pair of frictional snubbing members thereon longitudinally spaced from each other sufficient to permit the passage of a single layer of the flexible element therebetween a first of said snubbing members being positioned substantially on the longitudinal axis of the body member and the second of said snubbing members being spaced to one side of the longitudinal axis of the body member, guide means on said body member, said guide means having a portion parallel to the longitudinal axis of the body member and a curved abutment portion spaced from the periphery of the second snubbing member such that a portion of the flexible element positioned in the guide means in contact with the curved portion thereof will frictionally and radially contact at least a portion of a loop or bight passing around the second snubbing member, said flexible element being secured to said body member by a bight encircling the first snubbing member and the continuation of the flexible member forming a bight of opposite hand around the second snubbing member, a second loop in frictional radial contact with the bight on the first snubbing member and extending through the guide means in radial and frictional contact with the bight on the second snubbing element whereby application of tension load to the flexible element will cause a compressing of the bights around the snubbing elements to thereby increase the frictional snubbing action thereof.
